UNITED STATES PATENT OFFICE.

PETER L. PETERSON, OF WORCESTER, MASSACHUSETTS.

WIRE CONNECTION FOR STRAIN-INSULATORS.

1,374,229.

Specification of Letters Patent.

Patented Apr. 12, 1921.

Application filed August 15, 1919. Serial No. 317,829.

To all whom it may concern:

Be it known that I, PETER L. PETERSON, a citizen of the United States, residing at Worcester, in the county of Worcester and State of Massachusetts, have invented a new and useful Wire Connection for Strain-Insulators, of which the following is a specification.

This invention relates to a wire connection for a strain insulator, particularly designed for use in electrical transmission lines or in other electrical installations.

It is the common practice to use a single metal loop or clevis for this purpose, with a non-circular sleeve or thimble on the clevis, over which the wire is strained. This device is inconvenient to assemble and it is found difficult to hold the non-circular thimble in correct position while the wire is being strained around the thimble.

It is the object of my invention to improve the construction of wire connections for strain insulators and for other similar purposes by providing a grooved roll mounted between separate side plates, the connection being adapted to be easily assembled and connected to a strain insulator or other support.

A preferred form of my invention is shown in the drawings, in which—

Figure 1 is a side elevation of my improved connection in use with a strain insulator;

Fig. 2 is a sectional elevation of the parts shown in Fig. 1;

Fig. 3 is an enlarged side elevation of a connector, with one of the side plates removed, and

Fig. 4 is an enlarged view of the grooved roll.

Referring to the drawings, I have shown a strain insulator 10 of the usual type, having a metal cap 11, secured thereon, and a bolt or stud 12 secured therein and extending beneath the insulator.

My improved connector comprises a pair of side plates 13 and 14 having openings in their opposite ends, these plates being preferably duplicates and being also preferably formed with their two ends identical. A

grooved roll 15 is rotatably mounted upon a pin 16 extending through the openings in one end of the side plates 13 and 14, and through an opening in the roll 15. The pin 16 may be retained in position by a cotter-pin 17 or in any other convenient manner. A similar pin 18 extending through holes in the opposite ends of the plates 13 and 14 may be used to connect the plates to the stud 12 or to any other suitable support. The wire "W" is passed around the roll 15 and after being suitably strained is commonly held in position by a clamp 19 forming no part of my invention. The end of the wire may be bound down as indicated at 20 to 65 form a neat and secure fastening.

With this construction, the parts are much more easily assembled than with the device heretofore commonly used. As the wire is strained, the roll 15 turns upon the pin 16, decreasing the friction and permitting the wire to be more satisfactorily strained. The roll also is a good running fit upon the pin 16, whereas the old style thimble was necessarily provided with a very large opening in order that it might pass over the end of the clevis.

Having thus described my invention, it will be evident that changes and modifications can be made therein within the scope of my invention as set forth in the claim, and I do not wish to be otherwise limited to the details herein disclosed, but what I claim is:—

A separable wire connection for a strain insulator comprising a pair of duplicate independent side plates, a grooved roller positioned between said plates at one end thereof, and detachable connections between said plates, said connections comprising a pin extending through said plates at one end thereof and forming a bearing for said roller, a second pin extending through the opposite ends of said plates by which said plates may be connected to a support, and removable fastening devices for holding said pins in position.

In testimony whereof I have hereunto affixed my signature.

PETER L. PETERSON.
